UNITED STATES PATENT OFFICE.

VICTOR PLANCHON, OF LYON, FRANCE, ASSIGNOR TO SOCIÉTÉ DES PLAQUES ET PAPIERS PHOTOGRAPHIQUES, A. LUMIÈRE ET SES FILS, OF LYON, FRANCE.

PHOTOGRAPHIC FILM.

1,116,479.

Specification of Letters Patent. Patented Nov. 10, 1914.

Application filed May 13, 1907. Serial No. 373,437.

To all whom it may concern:

Be it known that I, VICTOR PLANCHON, a citizen of the Republic of France, residing at Lyon, in France, have invented a certain new and useful Photographic Film, of which the following is a specification.

This invention comprises a photographic film, which, by its construction, allows the usual bulky paper protecting-band used in roll-films to be dispensed with, and in which there is much less halation than in films of ordinary construction.

The film, according to this invention, comprises four layers—first, a sensitive gelatin emulsion, secondly, a celluloid support, thirdly, an agglutinant coating soluble in cold water, and fourthly, a layer of non-actinic insoluble gelatin permeable to water upon the back of said agglutinant coating.

Figure 1 of the accompanying drawings shows a part of the film in perspective, a part of the non-actinic layer being separated from the rest of the film; and Fig. 2 is a section of the film.

The celluloid support *b* and the emulsion layer *c* together constitute an ordinary film. The layer *a* is of soluble gelatin permeable to water, and is impregnated with a non-actinic pigment such as carbon, India ink, or a red dye such as anilin derivatives. Glycerin, gum or the like may be added to increase its permeability.

The layer *d* is of some agglutinant soluble in cold water such as gum arabic, tragacanth gum, sugar, glucose or the like, and serves to secure the layers *a* and *c* together until the developing operation, during which the de-

veloping solution permeates the layer *a*, dissolves the layer *d*, and thus releases the said layer *a*.

The complete backed film thus constructed can be used in rolls, or it may be used as "cut films" or film-packs without the necessity of using intermediate opaque papers. Moreover halation is more completely prevented than in ordinary films, as the non-actinic layer is in optical contact (through the layer *d*) with the celluloid support, whereas in the case of the ordinary film there was always an air-space between the celluloid support and the black paper.

What I claim as my invention and desire to secure by Letters Patent is:—

1. A photographic film consisting of a pellicular celluloid support having a sensitized coating on its face and an agglutinant coating soluble in cold water upon its back, and a pellicular layer of non-actinic insoluble gelatin permeable to water upon the back of said agglutinant coating.

2. A photographic film consisting of a pellicular celluloid support having a sensitized coating on its face and a layer of gum soluble in cold water upon its back, and a pellicular layer of non-actinic insoluble gelatin permeable to water upon the back of said layer of gum.

In testimony whereof I have signed my name to this specification in the presence of two subscribing witnesses.

VICTOR PLANCHON.
